UNITED STATES PATENT OFFICE

129,964

DESIGN FOR A TWO-UNIT LOCOMOTIVE BODY

Harold L. Hamilton, Los Altos, Calif., and William D. Otter, Oak Park, Ill., and Paul A. Meyer, Detroit, Mich., assignors to General Motors Corporation, Detroit, Mich., a corporation of Delaware

Application February 10, 1941, Serial No. 98,876

Term of patent 14 years

To all whom it may concern:

Be it known that we, Harold L. Hamilton, William D. Otter, and Paul A. Meyer, citizens of the United States, Harold L. Hamilton being a resident of Los Altos, county of Santa Clara, and State of California, William D. Otter being a resident of Oak Park, county of Cook, and State of Illinois, and Paul A. Meyer, a resident of Detroit, county of Wayne, and State of Michigan, have invented a new, original, and ornamental Design for a Two-Unit Locomotive Body, of which the following is a specification, reference being made to the accompanying drawing, forming a part thereof.

In the drawing:

Figure 1 is a side elevational view of a two-unit locomotive body showing our design.

Figure 2 is a view similar to Figure 1 but showing the opposite side of the two-unit locomotive body.

Figure 3 is a front elevational view thereof.

The appearance of the rear end portion of the two-unit locomotive body design is conventional.

We claim:

The ornamental design for a two-unit locomotive body, substantially as shown and described.

HAROLD L. HAMILTON.
WILLIAM D. OTTER.
PAUL A. MEYER.
